Primary Examiner — Elizabeth J Oswecki(74) *Attorney, Agent, or Firm* — Harness, Dickey & Pierce, P.L.C.(57) **CLAIM**

The ornamental design for the electrical current transducer, as shown and described above.

DESCRIPTION

FIG. 1 is top left perspective view of an electrical current transducer showing my new design;

FIG. 2 is bottom right perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side view thereof; and,

FIG. 8 is a right side view thereof.
